SECTIONAL COLLAPSIBLE PLAY PEN

James C. Hansen, St. Paul, Minn.

Application November 5, 1947, Serial No. 784,273

2 Claims. (Cl. 5—99)

1

My invention relates to an improvement in a sectional collapsible play pen for infants.

It is a feature of my invention to provide a play pen which is circular in form and devoid of undesirable corner sections.

It is a primary feature to provide a circular pen that is collapsible being formed of two semi-circular sections which are quickly and easily assembled by joining the free ends of the same. It is a feature to provide two semi-circular or arcuated sections with upper and lower rails of metal tubing or any other suitable material secured by upright members. The free ends of the upper and lower semi-circular tubing rails are joined by inserting a short plug in the end of the tubing so that it will project an equal distance into the free end of the tubing of the semi-circular section to be joined therewith. The ends of the tubular sections are further secured by a rubber or plastic cylindrical piece which covers the joint of the tubular sections.

It is a further feature to provide a means of retaining the semi-circular or arcuated sections together consisting in fastening hooks and turnbuckles fastened to the upright members adjacent the joint formed with the tubular rails.

The upright members which support the upper tubular rail are recessed into the underside of the upper rail and the top portion of the lower tubular base rail and secured by means of metal screw or any other suitable means.

A further feature of my invention resides in providing a floor for my play pen consisting of a mat constructed of canvas or plastic or any suitable material. The mat is provided with cut out portions so that it will fit around the upright members and project to the outer edge of the lower tubular base rail. It is a further feature to provide an outer edge of the mat with a drawstring to securely position the mat in the bottom of the pen with relation to the bottom portion of the upright members.

These features together with other details and objects will be more fully disclosed in the following specification and claims.

In the drawings:

Figure 1 is a plan view of my play pen.

Figure 2 is a side elevational view thereof.

Figure 3 is a view on the line 3—3 of Figure 2.

Figure 4 is a view on the line 4—4 of Figure 2.

Figure 5 is a view on the line 5—5 of Figure 2.

Figure 6 is a detailed sectional view on the line 6—6 of Figure 1.

With my play pen A I provide upper semi-circular sectional rails 10 and 11 and lower semi-

2

circular or arcuated sectional portions 12 and 13, which may be made of metal tubing or any desirable material. On the under side of the upper rails 10 and 11 are constructed the equally spaced holes 14 adapted to receive the upper end of the upright members or bars 15 which may be made of tubing, rod, or any suitable material. The lower portions 12 and 13 are constructed similarly to the rails 10 and 11 and have holes 15 adapted to receive the lower end of the upright members 15. The ends of the bar members 15 are secured in the holes 16 and 14 by metal screws 17 or any suitable means by inserting the screws 17 thru holes 17' formed in the upper surface of the upper semi-circular rails and the bottom surface of the lower semi-circular sectional portions 12 and 13, thus the upper rail 10 together with the lower semi-circular portion 12 joined together with the upright bar members 15 form a half section of my play pen. The semi-circular rail 11 and lower portion 13 together with upright members 15 secured thereto form the corresponding half of the play pen A. Thus the pen may be stored and shipped in sectional halves.

25 The free ends of the lower semi-circular portions 12 and 13 are joined at 18 by inserting a short plug 19 which is of sufficient length to extend into the free ends of the portions 12 and 13. The free ends of the portions 12 and 13 contact each other over the center of the plug 19. The free ends of the upper semi-circular rails 10 and 11 are joined in the same manner as the free ends of portions 12 and 13 as described above. The joints made as above described are further secured by slipping a cylindrical piece 20 made of rubber or plastic or any suitable material over the joint where the free ends of semi-circular portions 10 and 11 meet as well as where the ends of the portions 12 and 13 are joined.

30 20 The piece 20 fits tightly and does not leave a joint exposed that can be easily taken apart or injure an infant.

The outermost of the upright bar members 15 on each of the half sections of the pen A are held securely adjacent each other by the hooks 21 together with the turnbuckles 22 which construction holds the free end of the portions 10 and 11 and 12 and 13 tightly together with the plugs 19 in position as above described.

35 21 The upright bars 15 are spaced so that a small infant cannot get its head between the bars. Further, the hooks 21 and turnbuckles 22 are adjustably positioned so that the distance from the semi-circular portions is such that an infant 50 cannot get its head lodged between the same.

The floor B of my pen is constructed of the flat flat portion 23 which may be made of canvas, plastic, or any suitable material. The mat 23 is circular in shape and extends to the outer edge of the semi-circular sections 12 and 13. The notches 24 of the mat 23 are formed on the outer edge thereof and of such a distance apart that the notches fit around the upright bar members 15 when the mat 23 is flat and positioned within the bar members 15, the pen A being assembled.

On the outer edge of the mat 23 is provided a drawstring 25 which is positioned in a channel 26 formed on the outer periphery of the mat 23. The free ends of the drawstring 25 are pulled together when the mat 23 is in place and then tied forming a mat that fits closely to the upright members 15 and on top of the lower semi-circular portions 12 and 13 covering the entire floor area of the pen without straps or any objectionable fastening means that an infant might tamper with.

I claim:

1. A collapsible sectional play pen each section consisting of an upper arcuated rail, a lower arcuated member, rod means for securing said upper rail to said lower arcuated member, means for joining said sections, a circular bottom mat,

notches formed in the outer periphery of said mat to correspond with said rod means, and a drawstring on the outer edge of said mat for securing the same to the bottom of said pen.

2. A sectional collapsible play pen including two arcuated half sections each consisting of upper and lower arcuated portions, upright means for connecting said upper and lower arcuated portions, means for joining said sections, a circular bottom mat, notches formed in the outer periphery of said mat to correspond with said upright means, and means for removably securing said mat to the bottom of said pen.

JAMES C. HANSEN.
